R. W. CUDWORTH

CHECK BOOK CLAMP

Filed March 1, 1923

INVENTOR.
R. W. Cudworth

BY ATTORNEYS.

UNITED STATES PATENT OFFICE.

ROYAL W. CUDWORTH, OF SAN FRANCISCO, CALIFORNIA.

CHECK-BOOK CLAMP.

Application filed March 1, 1923. Serial No. 622,153.

To all whom it may concern:

Be it known that I, ROYAL W. CUDWORTH, a citizen of the United States, and a resident of San Francisco, county of San Francisco, 5 State of California, have invented a new and useful Check-Book Clamp, of which the following is a specification.

The present invention relates to improvements in clamps or holders for check books 10 or the like and its object is to provide means for holding a folding check book in a flattened condition when the same is to be used. Folding check books, as now commonly used, can be written on with difficulty only 15 since the leaves have a tendency to fold and particularly since very often a firm support cannot be had for the check book when writing out a check.

My check book clamp is particularly designed to slidably engage the leaves of the 20 check book so that it may be slid into an inactive position where it does not interfere with the folding of the book and into an active position where it straightens out and 25 flattens the fold so that a check may be written conveniently.

The preferred form of the invention is illustrated in the accompanying drawing in 30 which Figure 1 shows a plan view of an unfolded check book having my clamp attached thereto, Figure 2 a section taken along line II-II of Figure 1, Figure 3 a section taken along line III-III of Figure 1 and Figure 4 a perspective view of my 35 clamp taken by itself. While I have shown only the preferred form of the invention it should be understood that various changes or modifications may be made within the scope of the claims hereto attached without 40 departing from the spirit of the invention.

The check book (1) is made in the usual manner comprising a back (2) usually made of somewhat heavier material, the stubs (3) attached thereto in any suitable manner and 45 the blank checks (4) joined to the stubs along a perforated line (6). The check book, as ordinarily constructed, is adapted to be folded along a line substantially mid-

way between the left hand side of the stubs and the right hand edge of the back and is 50 held in that position by a flap (7) overlapping the right edge (8) and secured by means of a snap (9).

My clamp (11) shown in detail in Figure 4 comprises a back (12) coextensive in width 55 with the width of the check book and of convenient length to well cover the folded portion of the check book, two flanges (13) rising from the back on opposite sides of the check book and spring members (14) 60 adapted to slidably engage the upper and lower edges of the checks. The spring members are presented as leaves curled at both ends as shown at (16) and having a central portion (17) secured to the flanges (13). 65

The use of my clamp will be readily understood from the foregoing description. The clamp may be slipped over the book when the same is in an unfolded condition. To allow the check book to be folded it is 70 slid to engage a normally straight portion of the check book. When the check book is to be used the clamp is slid over the folded portion whereby the whole check book is straightened out and allows a check to be 75 written out without difficulty.

I claim:

1. A clamp for a book of the character described comprising a back member adapted to lie against the back of the book, flanges 80 rising from said member on opposite edges of the book, and a leaf spring secured to either flange having curled ends adapted to bear on the leaves of the book for flattening the same.

2. A clamp for a book of the character described comprising a back member adapted to lie against the back of the book, flanges 90 rising from said member on opposite edges of the book, and a leaf spring for each flange having a central portion attached thereto and having curled ends adapted to bear on the leaves of the book for flattening the same.

ROYAL W. CUDWORTH.
